(57) **CLAIM**

The ornamental design for an electrogustometer electrode, as shown and described.

DESCRIPTION

FIG. 1 is a top perspective view of an electrogustometer electrode showing my new design;

FIG. 2 is a bottom perspective view thereof;

FIG. 3 is a bottom plan view thereof;

FIG. 4 is a front elevation view thereof;

FIG. 5 is a top plan view thereof;

FIG. 6 is a left end view thereof; and,

FIG. 7 is a right end view thereof.

1 Claim, 2 Drawing Sheets
